UNITED STATES PATENT OFFICE

1,995,508

TANK HEATER

William R. Hartung, Des Moines, Iowa

Application February 9, 1931, Serial No. 514,526

6 Claims. (Cl. 126—360)

The object of my invention is to provide a simple, durable and inexpensive tank heater which is particularly adapted to be formed of cast iron, and having a minimum number of packing joints.

A further object is to provide a tank heater having a heat radiating member adapted to be supported in a submerged position and having a single vertically arranged pipe having its lower end communicating with the interior of said heating element and its upper end projecting above the water level, and to provide means whereby one portion of said pipe may be utilized as an intake and the other portion as an outlet for said heating element, whereby a single packing may be employed both for inlet and outlet passages.

A further object is to provide in a tank heater of that type having a horizontally supported heating chamber designed to be totally submerged and having inlet and outlet passages projecting upwardly above the water level and provided with an oil burner, improved means for creating an initial draft in the outlet pipe, whereby heated gases may be made to travel through the horizontally arranged heating element.

A further object is to provide in a tank heater of that type designed to employ an oil burner, improved means for supporting the supply tank and for feeding oil to said burner.

A further object is to provide in a tank heater having a vertically arranged inlet pipe, improved means for covering the pipe to prevent rain and dirt from entering the same.

This invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of my improved tank heater.

Figure 2 is a detail sectional view, taken on the line 2—2 of Figure 1.

Figure 3 is a detail sectional view, taken on the line 3—3 of Figure 1, and

Figure 4 is a detail sectional view, taken on the line 4—4 of Figure 3.

Referring to the accompanying drawing, I have used the reference numeral 10 to indicate the heating element, which is preferably of annular formation having a continuous passage 11 for conducting heated gases, legs 12 being provided for supporting the heating element 10 a slight distance above the tank bottom.

The upper surface of the member 10 is provided with openings 13, the upper surface of the member 10 being provided with a boss 14 formed around the edge of said openings and designed to support a vertically arranged tubular member 15, the lower end of the member 15 having a flange 16 which is secured to the boss 14 by means of bolts 17. A packing strip 18 is inserted between the members 14 and 16.

The tubular member 15 is elongated in cross section, as clearly illustrated in Figure 2, the sides of the member 15 being provided with inwardly projecting lugs 19 arranged in such manner as to support the vertically arranged partition plate 20, the lower end of the plate 20 terminating in the bottom edge of the passage 11, and its upper end terminating in the top edge of the member 15. The lower end of the partition 20 is provided with an opening 21.

Slidably mounted adjacent to the front face of the partition 20 is a damper plate 22 having its lower end designed to project downwardly into the passage 11. The partition 20 provides means for dividing the tube 15 into an inlet passage 23 and an outlet passage 24. The damper 22 closes the passage 11 so that one end communicates with the passage 23 and the opposite end with the passage 24, in the manner clearly illustrated in Figure 3, so that air moving downwardly through the passage 23 must travel throughout the entire length of the passage 11 and be finally delivered to the passage 24.

The damper 22 is provided with an opening 25 which is adapted to align with the opening 21 when said damper is in an elevated position. The upper end of the damper 22 is provided with an inwardly projecting flange 26 designed to support the lower end of the vertical rod 27, the upper end of which terminates in a horizontal handle portion 28, the said member 27 being slidably mounted in the cap casting 29, said casting being designed to fit on the upper end of the tubular member 15 and provided with an upwardly projecting thimble 30 designed to receive the lower end of a tubular stack 31.

The member 29 is also provided with laterally projecting lugs 32 to which a cover 33 is pivotally connected, said cover having one side projecting beyond one side of the casting 29, in the manner clearly illustrated in Figure 4, so that an air passage 34 is formed between the lower edge of one side of said cover and the upper edge of the cap member 29, communicating with the upper end of the inlet passage 23.

One side of the cap member 29 is provided with

a flange 35 to which one end of a semi-cylindrical plate 36 is fastened, the opposite end of said plate 36 being supported by a brace 37, the lower end of which is connected to a lug 38 projecting outwardly from the tube 15. The flange 35 is designed to support an annular member 39 designed to receive the inner end of a fuel tank 40, said tank being normally supported within the plate 36 in the manner clearly illustrated in Figure 1. 5

10 The inner end of the tank 40 has a pipe 41 projecting horizontally and inwardly over the upper end of the tubular member 15. The inner end of the pipe 41 is provided with a petcock 42 which provides means for adjusting the flow of 10 fuel, said fuel being adapted to drip into the upper end of a funnel-shaped member 43 mounted on the upper end of the tube 44, said tube 44 having its lower end connected to a burner 45, 15 said burner being mounted in the inlet end of the passage 11 and beneath the lower end of the inlet pipe 23. The burner 45 is provided with a slot 46 through which the gas from the burner is discharged, combustion taking place immediately around the body of the burner and beneath the 20 lower end of the inlet pipe 23, so that heated 25 gases from said burner will be drawn through the passage 11 in a counter-clockwise direction, as illustrated in Figure 2, and finally discharged through the passage 24. The details of my burner 45 constitute the subject matter of my co-pending application, Serial Number 514,527, filed February 9, 1931 now Patent No. 1,965,835, issued July 10, 1934.

35 In all types of tank heaters in which the heating element is submerged beneath the water and in which are provided vertical inlet and outlet pipes, great difficulty exists in getting the burner started, due to the fact that any heated air from the burner has a tendency to rise in the inlet pipe 40 rather than to pass horizontally through the long passage of the heating element and out through the stack. To overcome this difficulty the damper 22 has been provided and is so arranged that at the time the burner 45 is being 45 lit the said damper plate is elevated, which will then permit the heated gases from the burner to rise upwardly through the passage 24 and will thereby create a draft in the stack.

50 As soon as the gases within the stack have become heated, then the damper is moved to its closed position and the heavy air of the inlet pipe will cause the light air of the discharge pipe to be elevated and the draft will be created through the heating element.

55 To further assist in heating the air of the stack the openings 21 and 25 are provided, which are in alignment at the time the damper is in its elevated position.

60 In lighting the burner 45 the operator usually inserts, by means of a wire, a piece of waste or cotton which has been saturated with oil and ignited, and then lowers it into the inlet passage 23. This ignited lighter is inserted through the openings 25 and 21 into the passage 24, causing the air therein to become heated before attempting to start the burner. By this arrangement it will be readily seen that flames from the lighter when the lighter has been withdrawn to 65 passage 23 and the damper 22 has been lowered to closed position, will be drawn downwardly onto the top of the burner on account of the draft already started in the stack, and thereby provide means whereby the burner will be easily and quickly heated to such a temperature as to 70 become self-operating.

The burner 45 may be of any type particularly adapted to operate in position at the lower end of the inlet pipe 23, and which is provided with a supply tube 44. For that reason the detailed construction of the burner is not described or illustrated, and forms no part of my present invention. 5

Thus it will be seen that I have provided a tank heater of simple construction which may be easily formed of cast iron and provided with means whereby a single packing is utilized to communicate the burner element with the vertically arranged inlet pipe 23, and at the same time provided a heating element so constructed as not to easily warp or become leaky due to un- 15 even expansion.

Furthermore I have provided a heater which when provided with the proper burner has means whereby the burner may be easily and quickly started, and means whereby the device is comparatively safe, due to the fact that back firing of the burner is eliminated on account of the draft being created in the stack before the burner is ignited and before fuel is supplied thereto. 20

It will further be seen that I have provided improved means for covering the inlet pipe to exclude water and dirt, and further improved means for supporting the fuel tank in such a manner that the tank may be easily and quickly removed for filling, if so desired. 25

I claim as my invention:

1. A tank heater comprising an annular heating element having an annular passage therein, an inlet opening and an outlet opening, said openings being adjacent to each other, an upright pipe communicating with both of said openings, a partition plate extending longitudinally through said pipe and between said openings for dividing the pipe into inlet and outlet passages, said partition having an opening, a damper plate slidably mounted adjacent to one side of said partition and having one end adapted to project downwardly into said annular passage for dividing same between said inlet and outlet openings, the upper portion of said damper plate having an opening designed to align with the opening in said partition when the damper is raised to its open position, a burner mounted in the first passage and adjacent to said damper when closed and beneath said inlet passage, and means for feeding fuel to said burner. 30

2. A tank heater comprising a horizontal heating element having an annular passage for circulating heated gases and provided with adjacent and vertically arranged inlet and outlet openings in its upper surface, a damper supported transversely in said annular passage for communicating one end of said annular passage with said inlet opening and its opposite end with said outlet opening, said damper being adapted to move to an open position communicating the lower end of said inlet opening directly with the lower end of said outlet opening, a burner beneath the lower end of said inlet opening adjacent to said damper when in a closed position, means forming inlet and outlet passages communicating with said inlet and outlet openings, respectively, an opening communicating said inlet and outlet passages above said damper and above said burner, through which a torch may be inserted through the inlet passage into the inner end of said outlet passage to create a premature draft in the outlet passage, whereby said draft will first be moved downwardly over said burner into said outlet passage when the damper is opened and then 75

through said annular passage when the damper is closed, and means for closing the last said opening.

3. A tank heater comprising a hollow annular body member adapted to be supported horizontally and provided with adjacent inlet and outlet openings, a tubular member having one end communicating with both of said openings, a burner within said body and beneath said inlet opening, 5 a partition mounted longitudinally through said tubular member for dividing it into inlet and outlet passages and communicating with the respective openings of said body member, a damper in said body between the inlet and outlet openings, said partition having a by-pass opening above said damper through which a torch may be inserted through the inlet passage into the inner end of said outlet passage to create a premature draft in the outlet passage, whereby said draft will first be moved downwardly over said burner into said outlet passage when the damper is opened and then through said annular body when the damper is closed said damper being shaped to close said by-pass opening when the 10 damper is in its said closed position.

4. A tank heater comprising a body portion provided with a lower portion having a horizontal circuitous passageway and an upper portion having adjacent inlet and outlet passageways 15 communicating with said circuitous passageway at their lower ends, a damper supported transversely in said passageway for preventing direct communication of the lower ends of said inlet and outlet passageways when the damper is closed, and for permitting direct communication between their lower ends when the damper is opened, a burner in the inlet end of said circuitous passageway adjacent to said damper and 20

slightly below the lower end of said inlet passageway, the upper portion of said body having an opening communicating with said inlet and outlet passageways near their lower ends and above said burner, said damper being shaped to close the last said opening when in its said closed position, for the purposes stated.

5. A tank heater comprising a heating element formed with a circuitous passageway through which products of combustion may be passed for heating purposes, an upright pipe communicating with said circuitous passageway, a partition for dividing the upright pipe into inlet and outlet passageways communicating with said circuitous passageway, a burner in the inlet end of 10 said circuitous passageway, means for directly communicating the inner ends of said inlet and outlet passageways at a point below the top of said burner, means for directly communicating said inlet and outlet passageways at a point above 15 said burner, and means for opening and closing both of the last communicating means.

6. A tank heater comprising a heating element formed with a circuitous passageway through which products of combustion may be passed for heating purposes, upright conduit means communicating with said circuitous passageway to form inlet and outlet passageways communicating with said circuitous passageway, a burner in the inlet end of said circuitous passageway, means for directly communicating the inner ends of said inlet and outlet passageways at a point below the top of said burner, means for directly communicating said inlet and outlet passageways at a point above 20 said burner, and means for opening and closing both of the last communicating means. 25
